UNITED STATES PATENT OFFICE.

THEODORE KREIPE, OF FLORAL PARK, NEW YORK.

SAFETY DEVICE FOR POWER STAMPING-PRESSES.

1,129,301.

Specification of Letters Patent. Patented Feb. 23, 1915.

Application filed August 8, 1914. Serial No. 855,726.

To all whom it may concern:

Be it known that I, THEODORE KREIPE, a citizen of the United States, residing at Floral Park, Long Island, in the county of 5 Nassau and State of New York, have invented certain new and useful Improvements in Safety Devices for Power Stamping-Presses and the like; and I do hereby declare the following to be a full, clear, and 10 exact description of the invention, such as will enable others skilled in the art to which it appertains to make and use the same.

My invention relates to devices for safeguarding the operators of machinery and 15 especially machine tools of the character known as power presses, and it consists in the novel features hereinafter described, reference being had to the accompanying drawings which illustrate one embodiment 20 of my invention selected by me for the purpose of illustrating the same and the said invention is fully disclosed in the following description and claims.

Referring to the said drawings, Figure 1 25 represents a side elevation of a power press of well known type having my invention applied thereto. Fig. 2 represents a horizontal sectional view of the press just above the platen of the same, showing the press 30 platen and the adjacent parts of my improved safety device. Fig. 3 is an enlarged side elevation of the gate bar and connected parts, in detail. Fig. 4 is a horizontal sectional view of the gate bar bearing casting, 35 the bracket casting, the cam plate, and the supporting pivot. Fig. 5 is a detail view of the cam plate detached. Fig. 6 is a perspective view showing the outer end of the gate bar with one form of safety gate attached thereto and the adjustable connection which I prefer to employ between the gate 40 and gate bar. Fig. 7 is a detail view of the treadle piece for connecting the clutch rod with the treadle and securing lost motion 45 between the two as hereinafter described.

The object of my invention is to provide a safety device for power presses and the like tools in which the hands of the operator are required to place the material operated upon 50 in position which will positively prevent the possibility of the press or other device being operated while the hand of the operator is in such a position as to be liable to be injured. In this type of press the driving shaft carrying the balance wheel is operated

continuously and a suitable clutch mechanism is provided to connect the driving shaft with the operating parts of the press in order to effect the operation thereof, such clutch mechanism being operated for each 60 operation of the device by means under the control of the operator and ordinarily a treadle which is depressed by the foot of the operator. It frequently happens that the operator depresses the treadle before removing his hands out of reach of the plunger or other moving part of the press, with the result that injury to and maiming of the operator ensues.

My invention provides an extremely simple safety mechanism which can be applied to any of the forms of power presses, and many other devices, now in general use, by any ordinary mechanic without any material alteration of the press or any of the 70 operative parts thereof, and which will positively preclude the operation of the press by means of the clutch operating rod until after the hands of the operator have been removed from dangerous proximity to the 75 plunger or other moving part.

In the accompanying drawings which illustrate one embodiment of the invention, selected by me for purposes of illustration, 1 represents a bracket casting or plate provided with apertures 2-2 by means of which it may be screwed or bolted to the frame of the press, for example, one of the webs 3 of the frame of the press illustrated in Fig. 1, the said plate 1 being provided with a pivot pin 4 projecting horizontally therefrom and said plate is also provided preferably with stop lugs 5, and 6, as shown in Fig. 3, for limiting the movements of the gate bar, as hereinafter described, one or 85 both of these stop lugs may be provided with adjustable stops. In Fig. 3, for example, the stop lug 6 is provided with an adjustable stop screw 7 and set nut 8 adjustably regulating the upward throw of the 90 gate bar. The pivot pin 4 may be formed integral with the plate 1 or separately and secured thereto in any desired manner.

Upon the pivot pin 4 is mounted the 105 swinging gate bar and I prefer to form this in two parts, to wit, the gate bar proper indicated at 9, and the gate bar pivot casting indicated at 10. This casting is provided with a bearing aperture engaging the pivot pin 4 and with a longitudinally grooved por- 110

tion to receive the gate bar 9 which may be made of plain stock, rectangular in cross section and secured to the casting 10 by bolts 11, as shown. The casting 10 is also 5 provided preferably with a short stop arm 12 projecting rearwardly of the pivot 4 and lying between the stop lugs 5 and 6, and to this stop arm is preferably secured a counterbalance spring 13, one end of which may 10 be secured to a suitable aperture in the end of the stop arm 12, the other end being secured to the frame of the machine, as for example, by means of a screw 14 screwed into the frame or web 3 as herein shown. 15 The gate bar is provided with a slotted portion of peculiar formation, and for convenience I prefer to form this slot in a separate part secured to the stop arm and adjustable with respect thereto. In this instance, I have shown for this purpose what 20 I term the cam plate 15 shown in detail in Fig. 5, said plate being provided at one end with an aperture to engage the pivot pin 4 and at the other end with a segmental slot 25 16 curved concentrically with the axis of the pivot pin 4 and engaging a set screw 17, which passes through the slot and into a boss 18 on the casting 10, said boss and an extended portion 19 of the bearing portion 30 of the casting 10 serving to hold the cam plate 15 parallel with the gate bar 9. The cam plate is also preferably provided with adjusting screws 20 and 21 extending from opposite ends of the slot 16 and adapted to 35 impinge at opposite sides of the set screw 17 so that the adjustment between the cam plate and the gate bar will not be disturbed, even though the set screw 17 should become loosened. This is important, for the reason 40 that a single failure on the part of a safety device of this character to operate may result in the loss of a finger or other injury to the operator. The cam plate 15 is provided with a cam slot 22 which has two portions 45 disposed at an angle to each other. The upper portion of the slot extends in a direction toward the axis of the pivot pin 4 and is provided at its lower side with a shoulder 23. The other portion of the slot extends 50 downwardly from the upper portion and preferably in a forwardly inclined direction, as shown, providing the inclined edge or face 24, and the upper portion of the slot has a curved upper edge 25 extending laterally in a direction toward the pivot pin 4 beyond the junction of the shoulder 23 with the inclined edge 24, for the purpose herein-after explained. 55 The outer end of the gate bar 9 carries 60 the safety gate which may be of any desired shape or form so that in its descent it will come in contact with the hands of the operator should they be within dangerous proximity of the working parts, as the plunger of the press. In order to adapt my improved 65 device to various machines, I provide means for securing the gate to the gate bar in such a manner that it may be adjusted longitudinally of the gate bar and also vertically with respect thereto. In the present instance I 70 have shown the gate as consisting of a horizontally disposed bar 26 provided with a vertically disposed stem 27 which extends upwardly through a vertical aperture in a clamping block 28, said block being provided 75 with a horizontal aperture through which the gate bar 9 passes, and which communicates with the vertical aperture so that the stem 27 directly engages the inner face of the gate bar 9. The block 28 is provided 80 with a set screw 29 to engage the gate bar 9, and when this set screw is turned up it will not only secure the block to the gate bar 9, but will clamp the stem 27 firmly against 85 the inner face of the gate bar. Obviously 90 the gate and block 28 may be adjusted longitudinally upon the gate bar and the gate itself may be adjusted vertically by moving the stem 27 vertically with respect to the block 28, as clearly shown in Figs. 3 and 6. 95 The gate 26 is preferably provided with rearwardly extending arms 30 which are conveniently formed by bending a piece of metal into U-shape and securing a central portion thereof to the gate 26 as indicated in Fig. 6. In practice, I prefer to have the gate 26 so mounted as to rest upon the platen of the press or other horizontal part when in its lowermost position, and the arms 30 will preferably extend rearwardly on opposite sides of the plunger at suitable distances therefrom, the exact form and arrangement of the arms 30 being determined by the character of the members and the work to be produced thereby. The arms 30 100 may be omitted if desired and the shape and form of the gate 26 may be changed to meet the requirements of different machines. 105 As the clutch mechanism of power presses must necessarily be sensitive so as to throw in the clutch and operate the press instantly on the depression of the treadle, I provide 110 that the clutch rod shall not be operated at all until the hands of the operator have been removed out of dangerous proximity to the plunger and to this end I provide for lost motion between the treadle and the clutch operating rod of the press. In Fig. 1, the clutch rod is indicated at 31, the upper end being connected operatively in any desired 115 manner with any desired or usual form of clutch mechanism so that the depression of the clutch rod 31 will throw in the clutch and cause the operation of the press. I provide the lower end of the clutch rod preferably with a yoke or treadle piece 32 shown in detail in Fig. 7, having a central aperture through which the treadle 33 passes and provided with vertical slots 34 to receive a pin 35 carried by the treadle, for 120 125 130

holding the parts in operative relation. In order to adjust the extent of lost motion accurately, I prefer to provide the treadle piece 32 at the bottom with a set screw 36 and set nut 37, the set screw extending up through the bottom of the treadle piece in position to be engaged by the treadle when the latter is moved downwardly. It will thus be seen that the treadle can be moved 10 downwardly to a considerable extent without affecting the clutch rod 31 at all, and the treadle will also be provided with a retraction spring 38 for restoring it and also the arm and safety gate to their highest positions. The treadle is also connected to the gate bar in such manner as to secure the movement of the gate into operative position before the treadle engages the screw 36 and commences to move the clutch rod 31. To this end I employ a connecting rod which is preferably formed in two parts, as shown at 40 and 40^a, and which inclines rearwardly from its lower end to the upper end, the lower part being pivoted to the treadle, and the upper part being provided with a yoke 41 carrying a friction roller 42, the said yoke embracing the cam plate 15 and the friction roller 42 lying normally in the rear end of the upper portion of the slot 22 and upon the shoulder 23. The two parts 40 and 40^a of the connecting rod are adjustably connected in any suitable manner, as by a clamp 43 or turn-buckle or their equivalent device, so that the proper adjustment of the parts 35 may be secured.

In applying my improved safety device to any ordinary power press or other similar machine, it is only necessary to secure the bracket plate 1 to the machine frame as shown, and the lower end of the spring 13 by means of the screw 14, to connect the lower end of the rod 40-40^a to the treadle forward of the position occupied by its upper end at its connection with the cam plate 15, and to insert the yoke 32 between the lower end of the clutch rod and the treadle, all of which is extremely simple and can be performed by any ordinary mechanic. The spring 38 normally holds the gate bar in 50 elevated position as shown in Figs. 1 and 3, the gate being held in such position that the operator is afforded full opportunity to place the stock in and remove it from the press when the gate is raised. If it is desired to operate the press, the operator will 55 depress the treadle 33 which at first merely draws down the rod 40-40^a without operating the clutch rod. The shoulder 23 normally extends in an inclined position 60 downwardly toward the axis of the pivot pin 4 so that the downward pull of the rod 40-40^a causes the friction roller 42 to pull down on said shoulder and depress the gate bar and gate into the position indicated in dotted lines in Fig. 1 when the shoulder 23

will have been brought into and have passed slightly below a horizontal position, causing it to incline downwardly away from the pivot pin 4. Thereupon the friction roller 42 will slide off of shoulder 23 and 70 down the incline 24, exerting a certain amount of downward pressure upon said incline, and retaining the gate bar and gate in lowered position and permitting the further movement of the treadle, which will 75 engage the adjusting screw 36 of the yoke 32 and depress the clutch rod, during the movement of the friction roller 42, down the inclined edge 24 of the slot 22. It will thus be seen that the shoulder 23 and the 80 downwardly extending portion 22 of the slot provide lost motion between the actuating roller 42, and the gate bar after the gate has been fully moved into operative position, while the connection between the 85 clutch rod and the treadle, (to wit, the yoke 32 and screw 36) provide for lost motion between the treadle and clutch rod before the gate is fully moved to operative position. It will thus be seen that if the operator 90 presses downwardly upon the treadle before removing his hands to a place of safety, that is to say, out of range of the gate 26 or its arms 30, the gate will be arrested in its descent by the operator's hand 95 or hands before the cam plate 15 reaches such a position as to permit the friction roller 42 to disengage the shoulder 23, and the treadle will be thus arrested before it can contact with the set screw 36 and operate the clutch rod. As the descent of the 100 treadle and gate bar is opposed by the retraction of the spring 38, and as the arm 9 and gate bar are counterbalanced by spring 13 the said springs tend to counterbalance 105 the weight of said parts and the pressure exerted on the treadle, so that the operator's hand will not be injured by the gate while the treadle will be positively held from operating the clutch rod in the slightest degree.

It is important to note that in my improved invention the clutch rod cannot be moved at all, even to the slightest extent until the operator's hands have been removed to a place of safety and the gate has descended to the limit of its downward movement. This is important for the reason that where it is possible to move the clutch rod at all during the descent of the gate, and reliance is had on the fact that it would not be moved so far as to cause the operation of the clutch until after the gate had reached its lowest position, the resulting operation might be seriously affected by 115 the wear of parts connected with the clutch, which might cause the clutch to come into operation sooner than was otherwise expected and so defeat the object of the safety device, but as in my device the clutch rod 120

is not actuated at all until the gate reaches its lowest position, the operation of my device is rendered absolutely safe and certain. After the operation of the machine the operator removes his foot from the treadle and the treadle and gate bar will be raised to their normal positions, as shown in full lines in Fig. 1, by the spring 38. The spring 38 as shown is a heavier spring than 10 the counterbalance spring 13 which counterbalances the arm 9 and parts carried thereby without being sufficiently strong to raise said arm and the gate from their lowest position. As the treadle rises, it lifts the 15 rod 40-40^a causing the roller 42 to travel upwardly through the inclined portion 22 of the slot in the cam plate 15 and bringing the roller 42 into engagement with the portion 25 at the upper edge of the slot, at 20 which time the clutch rod 31 will have moved upwardly with the treadle far enough to return it to normal position, before the upward movement of the gate is effected. The further upward movement of 25 the treadle and rod 40-40^a raises the arm 9 and the gate to their highest position in which they are arrested by the stop lug or set screw therein. At the same time the curved portion 25 of the cam plate throws 30 the friction roller backward over the shoulder 23 leaving it in position for the next operation. The rearward inclination of the rod 40-40^a also tends by its own weight to throw the friction roller to the rear end 35 of the slot as soon as it passes above the shoulder 23, thus assisting in restoring the parts to their original positions. The adjustability of the cam plate 15 with respect to the gate bar and the pivot casting 10 connected therewith, will enable the device to 40 be readily adjusted with respect to the press whether the press stands vertically or is inclined rearwardly, and the device as shown and described, may be readily and quickly 45 applied to and adjusted with respect to practically any of the power presses or other machines with which it may be found desirable to use it.

While I have described my improved 50 safety device as operatively connected with a treadle adapted to be operated by the foot of the operator, it is obvious that it is equally applicable to machines in which a hand operated lever or other starting device 55 is employed instead of a foot operated treadle.

What I claim and desire to secure by Letters Patent is:—

1. In a safety device for power presses 60 and the like, the combination with a movable gate bar provided with a part having a substantially horizontally disposed shoulder, provided at one end with an angularly disposed face, a safety gate carried by said gate bar, a connecting device adapted to be

connected with a movable operating part which controls the operation of the press, said connecting device having an actuating part for engaging the shoulder and effecting the movement of the gate into operative position, said actuating part normally lying above said shoulder but movable longitudinally of the same, to permit it to pass off of said shoulder, at the junction of said angular face therewith, when the gate has been 75 fully moved to operative position and permit the further movement of the operating part, and means for restoring the parts to normal position.

2. In a safety device for power presses 80 and the like, the combination with a movable gate bar provided with a part having a substantially horizontally disposed shoulder terminating at one end in an angularly disposed face, and having a substantially horizontally disposed face located above said shoulder and extending beyond the same at the end adjacent to said inclined face, a safety gate carried by said gate bar, a connecting device having one end provided with 85 means for connecting it to a movable operating part which controls the operation of the press, said connecting device having an actuating part for engaging the shoulder and effecting the movement of the gate into 90 operative position, said actuating part normally lying above said shoulder and below said horizontally disposed face, but movable longitudinally of said shoulder and face, to permit said actuating part to pass off of said 100 shoulder when the gate has been moved to operative position and permit the further movement of the operating part when the said connecting device is moved in one direction, and to permit said actuating device 105 to engage said face above said shoulder on the return movement of said actuating device, and means for restoring the parts to normal position.

3. In a safety device for power presses 110 and the like, the combination with a pivoted gate bar provided with a part having a substantially horizontally disposed shoulder inclining downwardly toward the axis of said pivotal connection, and provided at the end 115 farthest from said pivotal connection with a downwardly extending face, a safety gate carried by said gate bar, a connecting device provided at one end with means adapted to connect it with a movable part which 120 throws the press into operation, said connecting device having an actuating part for engaging the shoulder and effecting the movement of the gate into operative position, said actuating part normally lying 125 above said shoulder and movable longitudinally thereof, to permit it to slide off of said shoulder when the latter is moved with the gate bar into such position that it is inclined downwardly from the said pivoted 130

connection, to permit a further movement of the operating part, and yielding means for restoring said parts to normal position.

4. In a safety device for power presses and the like, the combination with a pivoted gate bar provided with a part having a substantially horizontally disposed shoulder inclining downwardly toward the axis of said pivotal connection, and provided at the end 10 farthest from said pivotal connection with a downwardly extending face, a safety gate carried by said gate bar, a connecting device provided at one end with means adapted to connect it with a movable part which throws 15 the press into operation, said connecting device having an actuating part for engaging the shoulder and effecting the movement of the gate into operative position, said actuating part normally lying above said shoulder 20 and movable longitudinally thereof, to permit it to slide off of said shoulder when the latter is moved with the gate bar into such position that it is inclined downwardly from the said pivoted connection, to permit 25 a further movement of the operating part, yielding means for restoring said parts to normal position and means for adjusting the part provided with the said shoulder with respect to the gate bar.

30 5. In a safety device for power presses and the like, the combination of a pivoted gate bar, of a cam plate operatively connected therewith and provided with a slot having portions disposed angularly to each 35 other to form a substantially horizontally disposed shoulder, a portion of said slot extending downwardly from one end of said shoulder, a connecting device adapted to be connected at its lower end with a movable 40 part constituting the means for effecting the operation of the press, said connecting device being provided at its upper end with an actuating part extending into said slot and engaging said shoulder, and yielding means 45 for maintaining the gate bar in inoperative position.

6. In a safety device for power presses and the like, the combination of a pivoted gate bar provided with a part having a substantially horizontally disposed shoulder, a safety gate carried by said gate bar, a connecting rod having its lower end provided with means for attaching it to a movable clutch actuating part, said connecting device 55 having an actuating part movably engaging said shoulder, yielding means for holding said gate bar in inoperative position, and said shoulder in operative relation with said actuating part, and means for providing lost 60 motion between said clutch actuating part and the clutch.

7. In a safety device for power presses and the like, the combination of a pivoted gate bar having a part provided with a slot, 65 having angularly disposed portions forming

a substantially horizontally disposed shoulder, said slot having a downwardly extending portion adjacent to one end of said shoulder, a connecting rod provided at one end with means for connecting it to a clutch 70 operating part of the press and at the other end with an actuating part extending into said slot and engaging said shoulder, yielding means for normally maintaining the gate bar in inoperative position and said shoulder in a position inclined downwardly 75 toward the axis of movement of said slotted part, said slotted part being provided with a cam portion adjacent to the end of said shoulder for engaging said actuating part to assist in restoring it to position above 80 said shoulder after the gate bar has been actuated.

8. In a safety device for power presses and the like, the combination of a pivoted gate bar, a co-axially pivoted cam plate operatively connected therewith and provided with an angular slot forming a substantially horizontally disposed shoulder, said slot having a downwardly extending portion at one 90 end of said shoulder, a connecting rod provided at its lower end with means for operatively connecting it to a clutch rod operating device, and at its upper end with a friction roller extending into said slot and 95 normally engaging said shoulder, and yielding means for normally holding the gate bar in elevated position, and said shoulder in a position inclined downwardly toward said pivotal axis.

9. In a safety device for power presses and the like, the combination of a pivoted gate bar, a co-axially pivoted cam plate operatively connected therewith and provided with an angular slot forming a substantially horizontally disposed shoulder, said slot having a downwardly extending portion at one end of said shoulder, a connecting rod provided at its lower end with means for operatively connecting it to a clutch rod operating device, and at its upper end with a friction roller extending into said slot and normally engaging said shoulder, and yielding means for normally holding the gate bar in elevated position, and said shoulder in a position inclined downwardly toward said pivotal axis, and means for adjusting said cam plate about said pivotal axis with respect to said gate bar.

10. In a safety device for power presses and the like, the combination of a pivoted gate bar provided with a part having a substantially horizontally disposed shoulder, a safety gate carried by said gate bar and provided with a vertically disposed stem, a clamping device having an aperture to receive said stem, and an aperture to engage the gate bar, and means for securing said clamp to the gate bar and stem, a connecting device provided at one end with means 120

for engaging a clutch rod operating device and at the other end with an actuating part for movably engaging said shoulder, and yielding means for normally maintaining said gate bar in inoperative position and said shoulder in operative relation with said actuating part.

11. The combination with a power press, provided with a clutch rod, a pivoted treadle 10 for operating the same, and a retraction spring for said treadle, of a pivoted gate bar, a cam plate mounted co-axially therewith, means for adjustably securing said cam plate to said gate bar, said cam plate being 15 provided with a slot having angular portions forming a substantially horizontally disposed shoulder, said slot having a downwardly extending portion adjacent to one end of said shoulder, a connecting rod having 20 its lower end connected to said treadle and its upper end provided with a friction roller extending into said slot and normally engaging said shoulder, a counterbalance spring connected operatively with said gate bar and cam plate, yielding means operatively connected with the treadle for holding the gate bar in raised position and the said shoulder in a position inclined downwardly and rearwardly, and connections between 25 the treadle and the clutch rod of the press, providing for lost motion.

12. The combination with a power press,

provided with a clutch rod, a pivoted treadle for operating the same, and a retraction spring for said treadle, of a pivoted gate 35 bar, a cam plate mounted co-axially therewith, means for adjustably securing said cam plate to said gate bar, said cam plate being provided with a slot having angular portions forming a substantially horizontally disposed shoulder, said slot having a 40 downwardly extending portion adjacent to one end of said shoulder, a connecting rod having its lower end connected to said treadle and its upper end provided with a friction roller extending into said slot and normally engaging said shoulder, a counterbalance spring connected operatively with said gate bar and cam plate, a spring connected with the treadle for holding the gate 45 bar in raised position and the said shoulder in a position inclined downwardly and rearwardly, a yoke connected with said clutch rod and provided with vertically slotted portions to engage said treadle, to permit lost motion between the treadle and the clutch rod, and an adjustable part for varying the extent of said lost motion.

In testimony whereof I affix my signature, in the presence of two witnesses.

THEODORE KREIPE.
